UNITED STATES PATENT OFFICE.

PAUL DELANY, OF MONTGOMERY, ALABAMA, ASSIGNOR OF ONE-HALF TO
FRANK BALTZELL, OF SAME PLACE.

DESIGN FOR A RETRACKER.

SPECIFICATION forming part of Design No. 31,443, dated August 22, 1899.

Application filed July 27, 1899. Serial No. 725,336. Term of patent 14 years.

To all whom it may concern:

Be it known that I, PAUL DELANY, a citizen of the United States, residing at Montgomery, in the county of Montgomery and State of Alabama, have invented and produced a certain new and original Design for Retrackers; and I do declare the following to be a full, clear, and exact description of the invention, such as will enable others skilled in the art to which it appertains to make and use the same.

The invention relates to a new and original design for retrackers; and it consists of a design of the configuration shown in the accompanying drawings, in which—

Figure 1 is a perspective view of the retracker. Fig. 2 is a top plan view. Fig. 3 is a longitudinal sectional view. Fig. 4 is a cross-sectional view on the line $x x$ of Fig. 3.

The leading feature of the design comprises the body portion 1, having converging edges 2, vertically-extending side pieces 3, that project above and below the surface of the body portion, slots 4, transverse ribs 5, hand-holes 6, a cross-bolt 7, and laterally-projecting ears 8. The body portion, at its widest end, curves downwardly, as do also the upper edges of the flanges at that point.

What I claim is—

The design for a retracker, as herein shown and described.

In testimony whereof I have hereunto set my hand in presence of two subscribing witnesses.

PAUL DELANY.

Witnesses:

CHARLIE THORN,
E. F. FULLER.
